UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

RESILIENT SHACKLE FOR MINE CARS.

Application filed September 26, 1923. Serial No. 664,890.

This invention relates to improvements in resilient shackles for mine cars and the like.

The object of the invention is to provide a simple and relatively inexpensive device 5 adapted to act as a cushioning means for buff and draft shocks between vehicles, the arrangement being especially adapted for mine cars.

In the drawing forming a part of this 10 specification, Figure 1 is a vertical, longitudinal, sectional view of the adjacent ends of two mine cars, showing my improvements in connection therewith. Figure 2 is a top plan view of the structure illustrated in 15 Figure 1. And Figure 3 is a transverse, vertical, sectional view corresponding substantially to the line 3—3 of Figure 1.

In said drawing, each mine car is shown as provided with a suitable heavy flooring 10 20 and a vertical end wall 11, the flooring 10 being cut away to provide a pocket, as indicated at 12 to accommodate the connecting or coupling members. At opposite ends, each car is also provided with a draw bar 13, 25 Each draw bar is in the form of a flat plate extending through the end wall 11 and secured at its inner end to the flooring 10. Adjacent the outer end, each draw bar is provided with a downwardly projecting lug 14 30 abutting the end of the flooring 10. A bolt 15 extending through the draw bar, the outer end of the flooring 10 and a transversely extending reinforcing member 16 at the lower side of the flooring is preferably provided 35 to secure the outer end of the draw bar to the car.

The resilient shackle, as shown, comprises, broadly a pair of yokes A and B; a set of 40 spring plates C; and two blocks D and E swiveled to the respective draw bars of two adjacent cars.

The yoke A has side arms 17—17 and a connecting section 18 at one end, extended to form a hook 19, the extension being cut away 45 at opposite sides to provide abutment shoulders 20. As clearly shown in Figure 2, the yoke A is divided longitudinally, thereby providing two separable sections, to facilitate assembling of the parts. The parts of 50 the yoke may be secured together in any suitable manner, preferably by a bolt 120 extending through the part 18 thereof. At the

opposite end of the yoke A, the arms 17 are cut away on the inner sides as indicated at 21, thereby providing abutment shoulders 22. 55 Intermediate its ends, each arm 17 is enlarged as indicated at 23 and provided with an inwardly opening socket 24 having the inner surfaces of the front and rear walls thereof diverging toward the open side of 60 the socket.

The yoke B is embraced between the arms 17 of the yoke A and has one end thereof laterally enlarged as indicated at 25 to correspond to the cut away portion of the arms 65 17, thereby providing shoulders 122 adapted to co-act with the shoulders 22 of the yoke A. The enlarged end 25 of the yoke B is bifurcated as shown, providing a pair of arms 70 26, and the main portion of the yoke is provided with a transverse opening 27 having transversely curved front and rear walls.

The set of spring plates C, comprises a series of flat rectangular plates arranged in face to face contact, forming together a 75 spring unit adapted to absorb the shocks in buff and draft. The plates composing the set are vertically disposed, extend transversely through the opening 27 of the yoke B and have their opposite ends projecting into 80 the sockets 24 of the arms 17. As clearly shown in Figure 2, the smallest portion of each of the sockets 24 corresponds in size to the corresponding end of the set of plates, and the set of plates fits tightly between the 85 curved front and rear walls of the opening 27.

The blocks D and E are each provided with a centrally disposed, upwardly projecting, cylindrical stem 28, and the projecting 90 end of each draw bar is provided with an opening 29 adapted to receive the stem of one of the blocks. The stem of each block serves to swivelly connect the same to the corresponding draw bar, the block being 95 suspended below the draw bar by the stem 28 which projects above the draw bar and has a collar 30 fixed to the upper end thereof, bearing on the upper surface of the draw bar. The collar 30 is preferably secured to 100 the stem by a pin 31 extending therethrough and having the opposite ends upset to retain it in position. Each of the blocks D and E is thus swivelly supported with the

upper face thereof in contact with the under surface of the corresponding draw bar. To provide proper clearance so that the blocks D and E will have free swinging movement, each of the same is formed with a curved surface 32 adjacent the lug 14 of the corresponding draw bar 13.

The block E is preferably connected to the draw bar at the gate end of the car and the block D to the draw bar at the opposite end of the car, and the cars are so disposed when coupled that the block D on the end of one car is disposed in an opposed relation to the block E of the adjacent car. The block D 10 extends between the arms 26 of the bifurcated end of the yoke B and a pin 33 extending transversely through the block and the arms 26 serves to pivotally connect the yoke B to the block. The yoke A is also pivotally 15 connected to the block D by the pin 33, the latter extending through alined slots 34 in the arms 17. The yokes A and B are thus connected for relative sliding movement by the pin 33 and are adapted to be swung to 20 the dotted line position shown in Figure 1 so as to be out of the way to provide proper clearance when the car is in a restricted space as when the same is being handled on a mine hoist. It will be evident that the yokes A 25 and B are connected by means of the transversely extending spring plates to swing in unison. A handle 35 may also be provided at one side of the yoke A to facilitate the raising of the yokes in coupling the cars.

To assemble the parts, the plates C are first inserted in the opening of the yoke B, the parts of the yoke A are then placed in 30 position with the ends of the plates extending into the sockets thereof, and bolted together at one end by the bolt 120. The yokes A and B are then pivotally connected to the block D by the pin 33, which also serves to 35 hold the parts of the yoke A assembled.

The block E is extended outwardly beyond 40 the end of the draw bar 13 at the gate end of the car and is bifurcated as indicated at 45 36 to receive the hook portion 19 of the yoke A. A transversely extending bar 37 connects the outer ends of the arms of the bifurcated portion 36 and is preferably formed 50 integral with the same. The transversely extending bar 37 is adapted to co-act with the hook portion 19 of the yoke A in coupling the cars. As clearly shown in Figure 55 1, the opening of the hook portion 19 is elongated longitudinally, to permit relative movement between the yoke A and the block E so that the shocks in buff will be transmitted through the shoulders 20 of the yoke 60 engaging with the flat end portions of the arms of the bifurcated portion 36, thus relieving the bar 37 of undue strain. It will be evident that the force during draft is 65 transmitted directly from the hook to the bar 37 engaged by the same.

The normal position of the parts is that shown in Figures 1 and 2, the shoulders 122 and the front end of the yoke B being spaced respectively from the shoulders 22 and the inner face of the section 18 of the yoke A, 70 and the pin 33 disposed centrally of the slots 34 of the arms 17 of the yoke A. In draft, it is evident that, as the cars are pulled apart the yoke B will be pulled away from the yoke A while the latter is being held by engagement of the hook 19 with the adjacent car thus flexing the set of spring plates C, thereby absorbing the shocks.

In a buffing action, as the cars approach each other, the yoke B will be forced inwardly relatively to the yoke A, which is brought into abutment with the block E and held by engagement of the shoulders 20 at the ends of the arms of the forked portion of the block. During relative approach of the yokes A and B, the springs composing the set C will be flexed in the opposite direction to that just described, thereby taking up the buffing shocks. The flexing of the set of spring plates C will continue until the end of the yoke B is brought into abutment with the section 18 of the yoke A and the shoulders 122 and 22 are brought into engagement, whereupon the force will be transmitted directly through the yokes. In this connection it is pointed out that the curvature of the front and rear walls of the opening 27 in the yoke B and the diverging front and rear walls of the pockets 24 permit the proper flexing of the set of spring plates C so that a full resilient effect of the same may be obtained.

I have herein shown and described what I now consider the preferred manner of carrying out my invention, but the same is merely 105 illustrative and I contemplate all changes and modifications that come within the scope of the claims appended hereto.

I claim:

1. In a resilient shackle for mine cars, the 110 combination with a pair of relatively movable yokes; of resilient means opposing relative movement of said yokes; means for pivotally connecting one end of both of said yokes to a car; and means for detachably connecting the opposite end of one yoke to another car.

2. In a connector for cars, the combination 115 with a pair of relatively movable yokes; of a spring resistance unit opposing relative movement of said yokes; said unit extending transversely of said yokes and adapted to be flexed upon relative movement of said yokes; means for permanently connecting both of said yokes directly to a car; and means on one yoke for detachably connecting it to another car.

3. In a connector for cars, the combination 120 with a yoke having means thereon for detachably connecting it to a car; of spring 125

resistance means comprising a plurality of flexible plates co-acting with said yoke; and yoke means secured to another car for holding said spring plates, said holding means 5 and yoke being relatively movable.

4. In a connector for cars, the combination with a pair of yokes, both pivotally connected to one car, said yokes being mounted for relative sliding movement; of a spring resistance co-acting with said yokes, one of 10 said yokes having means thereon for detachably connecting the same to another car.

5. In a connector for cars, the combination with a yoke pivotally connected to one end of 15 a car; of a second yoke pivotally and slidably connected at one end to the same end of said car, said yokes being relatively slidable; spring plates extending through one of said yokes and engaging pockets in the other yoke; 20 and means for detachably connecting the other end of said second named yoke to another car.

6. In a connector for cars, the combination with a pair of relatively movable yokes; of 25 a spring resistance comprising a plurality of flexible plates opposing relative movement of said yokes; one of said yokes having means thereon for detachably connecting the same to a car; means for pivotally connecting said yokes to another car to swing in unison in a vertical plane, whereby said yokes may be dropped to a pendent position.

7. In a connector for cars, the combination with a pair of relatively movable yokes; of a 30 spring resistance coacting with said yokes; a block swiveled to one end of a car; and means

for securing the yokes to said block, including a slidable connection for one of said yokes.

8. In a connector for cars, the combination with means in the form of a pair of relatively movable yokes connected to one car, said means having a hooked portion at its free end, of a spring resistance co-acting with 40 said yokes; co-operating means adapted to be mounted on an adjacent car for detachably and pivotally connecting said second car with said yoke, said means including a fixed element detachably engageable by said hooked portion, the latter and said element 45 providing a slidable connection; and co-acting abutment faces on said last named means and yoke.

9. In a connector for cars, the combination with a resilient shackle connected at one end to one car and having a portion at its free end movable with reference to said first car said free end portion being provided with a hook; means resisting movement of said end portion in opposite directions; means adapted to be mounted on an adjacent car for detachably and pivotally connecting said second car with said movable end portion, said means including a fixed element adapted to cooperate with said hook to provide a sliding connection; and co-acting abutment faces 55 on said last named means and on said movable end portion.

In witness that I claim the foregoing I have hereunto subscribed my name this 21st 60 day of September 1923.

JOHN F. O'CONNOR.
